LACE

Aaron S. Staff, New York, N. Y.

Application July 11, 1951, Serial No. 15,820

Term of patent 14 years

(Cl. D47—6)

To all whom it may concern:

Be it known that I, Aaron S. Staff, a citizen of the United States, resident of Borough of Manhattan, city, county and State of New York, have invented a new, original, and ornamental Design for Lace, of which the following is a specification, reference being had to the accompanying drawing, forming a part hereof.

The figure is a face view of a lace, showing my new design.

I claim:

The ornamental design for a lace, as shown.

AARON S. STAFF.
